US00D830974S

(12) **United States Design Patent** (10) **Patent No.:** **US D830,974 S**
(45) **Date of Patent:** **** Oct. 16, 2018**

(54) **ELECTRICAL CONTACT ELEMENT**

(71) Applicant: **STAUBLI ELECTRICAL CONNECTORS AG**, Allschwil (CH)

(72) Inventors: **Tom Kufner**, Riehen (CH); **Philipp Alexander Strehler**, Basel (CH); **Fabian Hilti**, Ziefen (CH); **Lucas Wirz**, Basel (CH)

(73) Assignee: **STAUBLI ELECTRICAL CONNECTORS AG**, Allschwill (CH)

(**) Term: **15 Years**

(21) Appl. No.: **29/585,526**

(22) Filed: **Nov. 25, 2016**

(30) **Foreign Application Priority Data**

May 25, 2016 (WO) 967583401

(51) **LOC (11) Cl.** **13-03**

(52) **U.S. Cl.**

USPC **D13/154**

CLAIM

The ornamental design for an electrical contact element, as shown and described.

DESCRIPTION

FIG. 1 is a perspective view of an electrical contact element, showing our new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken line portion of the figure drawings is included to show portions of the article that form no part of the claimed design.

1 Claim, 4 Drawing Sheets
